BOTTOM CONNECTION HYDRAULIC
SETTING TOOL

Ruric N. Bean, Harold C. Block, and Leslie A. Layne, Houston, Tex.; said Bean and said Block assignors to said Layne

Application September 25, 1937, Serial No. 165,634

9 Claims. (Cl. 166—20)

The invention relates to a combination well bottom assembly and setting string and setting tool therefor wherein the setting tool will be released by the application of hydraulic pressure and the lower end of the well bottom closed simultaneously with the release of the setting tool.

It is one of the objects of the invention to provide an assembly wherein the well may be equipped with a set shoe, strainer, liner and packer, the well washed, and the packer set all in a single operation.

Another object of the invention is to provide a combination setting tool and wash valve which can be released and the wash valve closed by hydraulic pressure.

Another object of the invention is to provide a setting tool connection at the lower end of the well bottom which may be released by the application of hydraulic pressure.

Still another object is to provide a combination release plug for setting tools and a wash valve which can be moved to close the bottom of the well and to be latched in such closed position.

Other and further objects of the invention will be readily apparent when the following description is considered in connection with the accompanying drawings, wherein:

Fig. 1 is a side elevation of the upper end of the well bottom assembly showing certain of the parts in section and arranged as they are when the assembly is lowered into the well bore.

Fig. 2 is a side elevation showing a continuation of Fig. 1 to illustrate certain of the parts in section at the bottom of the assembly and showing the parts in position to receive the hydraulic pressure for releasing the tool and closing the wash valve.

Figs. 3 and 4 are side elevations of the upper and lower portions of the assembly respectively, but showing the parts after the setting has been accomplished and the packer collapsed.

The present invention relates to the general assembly shown in the co-pending application for patent of Leslie A. Layne, Harold C. Block and Albert L. Roco, Serial No. 122,948, filed January 29, 1937, and also to the general construction of a Setting tool such as shown in Patent No. 1,945,943, granted February 6, 1934, to Leslie A. Layne, and also to the co-pending application for patent of R. N. Bean, Serial No. 165,798, filed September 25, 1937, for a Hydraulic release for well bottoms.

In Fig. 1 the well casing is illustrated generally at 2 and terminates in the lower end 3 below which the well bottom assembly 4 is arranged to

project. This assembly includes the set shoe 5 which carries a back pressure valve 7 of the downwardly opening type which fits against a ring 8 mounted in the set shoe. This ring has an inner cylindrical face 9 which serves as a seat for the wash valve 10 which is slidably mounted inside of the nipple 11 which is connected to the set shoe and projects upwardly therefrom. A piece of blank pipe 14 may be connected to the well bottom above the set shoe by means of a coupling 15 or the strainer pipe 16 may be connected directly to the well bottom. The strainer 16 may be of any desired length and has the blank liner 17 connected thereabove. The upper end of the liner 17 is provided with a stop or shoulder 18 which forms part of the packer 19. Inside of the well bottom assembly 4 is the tubing or setting string 20 which may be a pipe of any desired diameter which carries a setting tool 21 and extends downwardly inside of the well bottom to terminate in a sleeve 22.

This sleeve is adjacent the upper end of the nipple 11 and carries a collar 23 which is provided with a plurality of spring fingers 25. These fingers extend downwardly below the collar 23 and have threaded outer faces thereon which are arranged to be received in the threaded area 27 inside of the nipple 11. In order to hold these fingers in connected position a combination expander block and wash valve 10 is positioned inside of the fingers, the cylindrical surface 28 thereof having been moved inside of the ends of the spring fingers to hold them in expanded position. This wash valve has an upstanding skirt 30 thereon which fits closely about the lower end 35 of this sleeve 22 so as to form a seal therewith.

In order that this wash valve will be held in position to maintain the fingers expanded, one or more locking pins 38 may be passed through the nipple 11 and into the wash valve as seen in Fig. 2. These locking pins will be inserted after the parts are assembled. The wash valve has a cylindrical passage 34 therein which leads to the discharge ports 36 so that washing liquid may be pumped downwardly through the setting string or wash pipe 20 and discharged through the shoe 5 when the pressure thereof is sufficient to open the back pressure valve 7.

It seems obvious that the weight of the well bottom assembly will be carried by the threaded connection 26—27 so that the entire weight of the assembly will be supported by the wash pipe or setting string 20. There will not be any load on the strainer 16, however, because this connection with the assembly is at the base thereof.

With the parts in the positions shown in Figs. 1 and 2 the entire apparatus will be lowered into the well bore until the set shoe rests on the bottom of the well.

- 5 The assembly can then be raised slightly and the washing operation carried on until the returns have cleared up to show that a majority of the drilling mud has been removed from the well. When it is desired to close the wash valve 10 a plug 48 will be deposited in the setting string 20 at the surface and carried down by the flow of liquid until it arrives in the wash valve as seen in Fig. 2. This plug may have a flexible packing 41 thereon to maintain a seal about it. As 15 this plug lands in the wash valve on the apex 42 thereof, it will form a seal to close the ports 35 so that hydraulic pressure applied through the setting string 20 will be available to shear the pin or pins 33 and cause the combination wash 20 valve and expander block to move downwardly to the position shown in Fig. 4.

This downward movement accomplishes two functions, namely, it closes the wash valve by moving the skirt 45 thereof into the cylindrical face 8 of the ring 8 so as to form a seal and positively close the lower end of the well bottom. The outer surface 46 of this skirt may be slightly tapered so that a wedging fit will be provided at this point to assist in holding the wash valve in 30 closed position and assist in stopping the valve. The sharp corner of this skirt 45 as it moves into the cylindrical face 8 will serve to shear off any obstruction that may have been deposited on the seat ring 8—in some instances small sticks or 35 twigs, gravel or nails may flow downwardly with the wash water and be deposited at this location due to the presence of the back pressure valve 7. This shearing action will tend to remove such obstructions and insure a seal. If desired a plurality of slip jaws 50 may be carried in the periphery of the wash valve and any upward movement of the wash valve after it is once set 40 will be prohibited by the wedging action of these slips as seen in Fig. 2.

45 The other function of the movement of this combination expander block and wash valve is to also be seen in Fig. 4 because the block has moved downwardly from its position within the lower end of the fingers 25 and due to the resilient nature of these fingers they will spring inwardly to release their threaded connection with the well bottom assembly, and they will assume the position shown in Fig. 4 as abutting against the sleeve 22.

50 The skirt 30 during this action moves downwardly a short distance along the sleeve 22 but not a sufficient distance to move away from the sleeve. If the operator now desires to find out whether his setting tool has released it is only necessary for him to raise the setting string 20 a short distance so that the lower end of the sleeve 22 moves out of the skirt 30. The operator can observe his pressure gauge at this time and by raising the setting string slightly there should be a drop in pressure because the pressure has been built up when the plug 48 closed off the ports 35 and when the sleeve 22 moves out of the skirt 30 the washing liquid inside of the setting string will be released into the annular space 51 inside of the strainer. This signal advises the operator that his tool has been released. On the other hand if no such signal is observed when he raises the wash pipe he is assured that the wash valve has not moved downwardly a sufficient amount to cause the release

75 and he may then increase his pump pressure until he does obtain a release.

If the operator wishes to be doubly sure that his wash valve is completely closed he may now lower the setting string 20 until the lower ends of the fingers 25 abut against the upper end of the skirt 30 and in this manner he may tamp the wash valve to be sure that it is in its lowermost position.

Another manner of releasing the tool would be 10 to raise the entire assembly a very short distance from the well bottom at the time the plug 48 is inserted. Thus when the pins 33 shear and the wash valve moves downwardly the setting tool connection would be released and the well bottom assembly 4 would drop a short distance onto the bottom of the well bore and this downward movement would carry the skirt 30 to a point below the end of the sleeve 22.

15 A circulation of liquid may now be had to 20 wash the inside of the screen and then the setting string 20 may be raised a sufficient amount to bring the setting tool 21 adjacent the elevation of the upper end 55 of the packer so that it will engage the shoulder 54. The weight of 25 the setting string may then be utilized to collapse the packer by moving the setting tool barrel 56 downwardly over the ratchet teeth 57 so that the upper shoulder 58 on the packer barrel is moved toward the stop or support 18 so that 30 the packing material 59 will be expanded as seen in Fig. 3.

35 This particular type of packer is known as an upside down packer because the lower support 18 remains stationary while the packer barrel 56 which carries the packing 59 moves downwardly. Such a packer is of advantage because the expansion of the packing begins at the base and progresses upwardly. Such an arrangement permits the setting of the packer with a 40 setting string of much lesser weight than other types of packers.

45 If desired a concrete shield 60 may be carried by the upper end of the packer to cling about the setting string 20 and prevent the entrance of sand or sediment into the well bottom assembly.

50 The set shoe 6 of course has the usual opening 62 therein but in addition may have the laterally and upwardly inclined ports 63. These ports are provided to allow discharge of the wash liquid 55 in a direction so that the bottom of the well bore will not be washed away. It has been found that in some instances the wash water discharging from the opening 62 would wash out a considerable hole so that when the washing operation was completed and the well bottom set the whole assembly would move down to rest on the bottom and the result would be the setting of the strainer at an elevation considerably below its calculated position. The lateral discharge of the wash water 60 has therefore been provided.

Broadly, the invention contemplates a combination wash valve and setting tool expander which may be raised to close the well bottom, release the setting tool, and signal the operator that 65 such release has been effected.

What is claimed is:

1. The combination of a well bottom assembly and a setting string and setting tool therefor comprising a plurality of spring fingers on said string, a wash valve and expander block beneath said fingers, a set shoe, shear means holding said valve in place so that said fingers are connected to said set shoe, hydraulically operable means to shear said means and move said valve to release 70

said connection and to move said valve to closed position.

5 2. A well bottom assembly, an hydraulic release setting tool connected thereto, a wash valve to hold said tool connected, and hydraulically operable means to move said valve to closed position and to release said connection.

10 3. A well bottom assembly, a setting tool connected thereto, a wash valve to hold said tool connected, hydraulically operable means to move said valve to release said tool, and means to latch said wash valve in closed position.

15 4. A combination expander block and wash valve for well bottom assemblies and setting tools therefor comprising a body, ports therethrough, and means to engage the setting tool to hold said tool connected to the well bottom.

20 5. A wash valve for well bottoms including a tapered skirt, discharge ports through said valve, a cylindrical surface to abut a setting tool, and an upstanding skirt portion to receive the wash pipe of the well bottom.

6. The combination of a well bottom assembly

and an hydraulic setting tool including a wash valve, hydraulic means to move said valve to closed position and to release said tool, and means on said tool to set the packer of said well bottom assembly.

7. In combination a well bottom, a wash string, and a cementitious cap carried by said string to deflect settling from said well bottom.

8. A wash pipe and wash valve, a plug to be pumped through said pipe to said valve, ports in said valve to be closed by said plug, and inter-engaging parts on said valve and pipe which are releasable to relieve the pressure in said pipe as an indication the pipe is released.

9. A set shoe for well bottoms comprising a body, a back pressure valve therein, a discharge opening in the base of said body, and laterally and upwardly inclined ports in said body below said valve.
